BENOIT DEMONT, OF PARIS, FRANCE.

AIR-COOLED EXPLOSION-ENGINE.

1,326,035.

Specification of Letters Patent. Patented Dec. 23, 1919.

Application filed October 15, 1918. Serial No. 258,222.

To all whom it may concern:

Be it known that I, BENOIT DEMONT, a citizen of the Republic of France, and a resident of 141 Avenue Malakoff, Paris, France, have invented new and useful Improvements in Air-Cooled Explosion-Engines, of which the following is a specification.

The present invention relates to a double-acting air-cooled explosion engine, which has as large as possible cooling surface for the minimum bulk or size.

This engine is characterized by the combination of a piston having upon its two faces, central reentrant portions of different diameters forming interior tubular passages reentering one interiorly of the other, and of a cylinder having upon its heads central reentrant portions of correspondingly different diameters also forming interior tubular passages reentering one interiorly of the other, the piston and the cylinder thus having each an exterior annular portion surrounding a central tubular portion formed on two tubes reentering one interiorly of the other.

It has already been proposed to form upon the heads of cylinders central tubular reentrant portions in which can enter corresponding tubular prolongations of the piston; but the central tubular portions of the two faces of the cylinder, or of the piston, were not of different diameters and did not enter one interiorly of the other, that is to say were not boxed one in the other as is the case in the present invention which arrangement enables the engine to be of greatly reduced dimensions in the longitudinal direction.

The annexed drawing represents in axial transverse section, one way of carrying out the present invention by way of example.

The exterior head a^1 of the cylinder a has a central part a^2 reentering interiorly in such a way as to form a central tubular passage arranged interiorly of an annular portion; this tubular passage is open at its exterior extremity and is provided at its inner extremity with a reinforcing wall a^3 , perforated with holes or openings a^4 .

The head a^1 of the cylinder has also a central portion a^2 reentering toward the interior and forming a central tubular passage; this passage is of a diameter greater than that of the tubular passage a^2 so that laterally it extends exteriorly in relation thereto.

The piston b on its exterior face b^1 also

has a central portion b^2 reentering inwardly and forms a tubular passage, open at its two extremities and capable of sliding with light friction around and exteriorly of the tubular passage a^2 . Further, the face b^1 of the piston has a central portion b^2 reentering toward the interior and forming a tubular passage of a diameter greater than that of the tubular passage b^2 and capable of sliding with light friction around and exteriorly of the tubular passage a^2 of the cylinder.

The piston thus comprises between the faces b^1 , b^2 and the tubular passage b^2 , an annular exterior portion arranged around a tubular central portion formed by the two tubes b^2 b^2 reentering one interiorly of the other. The same arrangement is effected in the cylinder.

The central portion b^2 of the piston is connected at b^3 to the piston rod c . Packing rings, piston-rings or the like a^5 a^5 are arranged near the interior extremity of each of the reentrant central portions a^2 and a^2 of the cylinder a , as well as upon the exterior surface of the piston b at b^4 . A wearing piece in the form of a liner d is preferably arranged within the cylinder a .

The arrangement of the present invention enables to be obtained with a very small bulk of the motor, a very large surface for air-cooling. This cooling is further increased by a double circulation of air (see the arrows); a current of air passes in the longitudinal axial direction of the engine to the interior of the tubular passages a^2 and a^2 by the openings or apertures b^5 formed in the wall of the tubular central portion b^2 of the piston, and by the openings or holes a^4 in the partition a^3 ; a second current of air traverses the motor in the transverse direction from the interior toward the exterior, passing from the central portion into the exterior annular portion of the piston b by means of openings b^6 formed in the interior wall b^2 of the piston, by openings b^7 in its exterior wall, and escapes to the exterior by the holes or apertures a^6 and d^1 formed respectively in the cylindrical body a and in the wearing piece d .

Having now particularly described and ascertained the nature of my said invention and in what manner the same is to be performed, I declare that what I claim is:—

1. In a double-acting air-cooled explosion engine, the combination with a piston having on its two faces reentrant central portions

of different diameters forming interior tubular passages reëntering one interiorly of the other, of a cylinder having upon its heads, reëntrant central portions of correspondingly different diameters also forming interior tubular passages reëntering one interiorly of the other, the piston and the cylinder thus having each an exterior annular portion surrounding a tubular central portion formed of two tubes reëntering one interiorly of the other.

2. In a construction such as specified in claim 1, ports in the piston and cylinder

walls permitting an air circulation in the longitudinal direction through the interior 15 tubular passages of the piston and of the cylinder, as also an air circulation in the transverse direction from the interior to the exterior through the piston and the cylinder.

In testimony whereof I have signed my 20 name to this specification.

BENOIT DEMONT.
